Wesley G. Carr
ATTORNEY

UNITED STATES PATENT OFFICE.

CARL H. KINDEL, OF PITTSBURGH, PENNSYLVANIA, ASSIGNOR, BY MESNE ASSIGNMENTS, TO ECLIPSE MACHINE COMPANY, OF ELMIRA HEIGHTS, NEW YORK, A CORPORATION OF NEW YORK.

ENGINE STARTER.

Application filed July 27, 1922. Serial No. 577,883.

My invention relates to engine starters and particularly to such starters as are automatically connected to and disconnected from the engines of motor vehicles.

5 One object of my invention is to provide an engine starter the operative engagement of which is automatically controlled in accordance with the operation of the engine.

A second object of my invention is to provide 10 an engine starter of the above-indicated character that is controlled by fluid pressure produced by the engine.

A third object of my invention is to provide 15 means whereby an engine starter may be automatically disconnected from the engine when the exhaust pressure of the latter reaches a predetermined value.

A further object of my invention is to provide 20 means whereby an engine starter may be maintained out of engagement with the engine when the latter is rotating without the occurrence of explosions in cylinders.

In the accompanying drawing, Fig. 1 is 25 a view, partially in elevation and partially in section, of a portion of an engine flywheel and a starting mechanism constructed in accordance with my invention that is associated therewith;

30 Fig. 2 is a view, similar to Fig. 1, illustrating the positions of the several parts when the starter is in its inoperative position.

An engine flywheel 1 is provided with 35 gear teeth 2 to be engaged by a pinion 3 that is driven by a starting motor 4, which may be an electric motor of the usual type. The pinion 3, which is splined on the armature shaft of the motor for longitudinal movement thereon and for rotation therewith, is controlled by a fluid-pressure mechanism 5 and a spring 6.

The fluid-pressure mechanism comprises 45 a cylinder 7 and a hollow piston 8 that is provided with an annular groove 9. A port 10 connects the groove 9 to the interior of the hollow piston 8. A pipe 12, which is connected to the cylinder at one end of the latter, is connected, at its other end, to the 50 exhaust pipe of the engine (not shown). A second pipe 13 is similarly connected, at one end, to an intermediate portion of the cylinder and, at its other end, to the intake pipe of the engine. The piston 8 is connect-

ed by means of a rod 14 to the pinion 3 for 55 longitudinal movement therewith.

Reference may now be had to Fig. 1 in which the various elements are illustrated in their respective positions that are assumed when the engine is not in operation. The 60 spring 6 exerts a force sufficient to retain the pinion 3 in operative engagement with the flywheel gear 2. When it is desired to start the engine, the circuit of the motor may be completed in any usual or suitable 65 manner to cause the motor to crank the engine. When the engine starts under its own power, the exhaust pressure produced by the explosions in the engine cylinders will be sufficient to cause the piston 8 to be actuated to the right, as viewed in the drawing, 70 until it assumes the position in which it is illustrated in Fig. 2.

When the groove 9 registers with the pipe 13 that is connected to the intake pipe of 75 the engine, the vacuum produced therein assists the exhaust pressure to retain the piston in the position in which it is illustrated in Fig. 2 to maintain the pinion 3 out of engagement with the flywheel. The connection to the intake pipe performs a useful 80 function in that the engine may be operated with the ignition circuit inoperative. In such case, the exhaust pressure will be relatively small, by reason of the absence 85 of explosion in the engine cylinders. There will, however, be no change in the degree of vacuum produced in the intake pipe under the different conditions. It will be noted that the opening of the pipe 13 is 90 closed except when the piston is in its outermost position, in which it is shown in Fig. 2.

The arrangement is so designed that the piston of the fluid-pressure mechanism is 95 retained in its outermost position so long as the engine is operating at an appreciable speed. When, however, the engine ceases to operate, the vacuum produced in the pipe 13 is substantially zero and the exhaust pressure in the pipe 12 is also approximately zero, whereby the spring 6 actuates the pinion 3 and its connected mechanism to the respective positions in which they are illustrated in Fig. 1. The mechanism is then in position 100 for the succeeding starting operation.

The employment of a starting mechanism 105 constructed and arranged in accordance with

my invention insures that the mechanism is operatively engaged in advance of the operation of the switch or other device for controlling the starting motor. The pinion 5 3 is actuated by its controlling spring into engagement with the flywheel without clash or shock that is incident to starting mechanisms in which the pinion is actuated into engagement while the motor is rotating at 10 a comparatively high speed. The fluid-pressure mechanism constitutes an arrangement by means of which the operative engagement of the starting mechanism may be controlled accurately according as the engine 15 is stationary or is operating at an appreciable speed.

What I claim as my invention:

1. The combination, with an internal combustion engine and its intake pipes, of a 20 starting means movable to engage and crank the engine, and means, comprising fluid-pressure mechanism operatively connected with the starting means and also connected to be actuated by the engine exhaust and the vacuum of the intake pipe, to hold the starting means disengaged.

2. The combination, with an internal combustion engine and its intake pipe, of a starting means movable to engage and crank the 30 engine, and means, comprising fluid-pressure mechanism operatively connected with the starting means and also connected to be actuated initially by the exhaust pressure of such engine and subsequently by the vacuum 35 of such intake pipe, to hold the starting means disengaged.

3. The combination, with an internal combustion engine and its intake pipe, of a starting means having a driving member shiftable into and out of engagement with the engine, means automatically operable normally to engage said driving member with said engine when the latter is stationary and means operatively connected with said 45 driving member and also connected to be actuated by the exhaust of the engine and by the vacuum in said intake pipe, to effect and maintain the disengagement of the driving member and engine when said engine is 50 running.

4. The combination, with an internal combustion engine and its intake pipes, of a starting means adapted to engage and crank the engine, and means comprising fluid-pres-

sure mechanism operatively connected with 55 the starting means, and actuated by the engine exhaust and the vacuum of the intake pipe to hold the starting means disengaged, said fluid pressure mechanism including a cylinder having ports communicating with 60 the engine exhaust and the intake pipe vacuum, and a piston reciprocable in the cylinder and actuating the starting means in its reciprocations.

5. The combination, with an internal combustion engine and its intake pipes, of a starting means adapted to engage and crank the engine, and means comprising fluid-pressure mechanism operatively connected with 70 the starting means, and actuated by the engine exhaust and the vacuum of the intake pipe to hold the starting means disengaged, said fluid pressure mechanism including a cylinder having ports communicating with the engine exhaust and the intake pipe vacuum, and a piston reciprocable in the cylinder 75 and controlling the said vacuum port to connect the same to one side of the piston, the said exhaust port constantly communicating with the cylinder on the other side of 80 the piston.

6. The combination with an engine and a starting mechanism therefor, of means for biasing a portion of said mechanism into engagement with said engine, and a cylinder 85 having a piston and having, also, a plurality of ports connected respectively to the exhaust pipe and to the intake pipe of said engine, whereby said piston opposes the force of said biasing means when the engine 90 is running.

7. The combination with an engine and a starting mechanism therefor, of means comprising a spring for biasing a member of said mechanism into engagement with said 95 engine and a cylinder having a piston therein and having, also, ports respectively connected to the exhaust pipe and to the intake pipe of said engine whereby said piston is actuated to oppose said spring with a force 100 that is dependent upon the exhaust pressure of the engine and the degree of intake vacuum.

In testimony whereof, I have hereunto subscribed my name this 15th day of July, 1922.

CARL H. KINDL.
